UNITED STATES PATENT OFFICE.

KATE L. TARBOX, OF NEW YORK, N. Y.

EMBROIDERY.

SPECIFICATION forming part of Letters Patent No. 279,042, dated June 5, 1883.

Application filed April 10, 1882. (Model.)

To all whom it may concern:

Be it known that I, KATE L. TARBOX, a citizen of the United States, residing at New York, in the county of New York and State of New 5 York, have invented certain new and useful Improvements in Embroidery, of which the following is a specification, reference being had therein to the accompanying drawings.

Figure 1 is a plan view, enlarged, of a piece 10 of cloth having my invention applied thereto. Fig. 2 is a transverse section taken on line xx , Fig. 1; and Fig. 3 is a transverse section taken on line yy , Fig. 1.

My invention may be applied to any cloth 15 which has a portion of its warp-threads, preferably at regular distances apart, raised above other portions of its warp-threads, looped around some of its woof-threads, passing between other warp-threads and looped around 20 other woof-threads, such portion of its warp-threads being caused to occupy a different path through the cloth in the process of weaving from the path which is pursued or occupied by any other warp-threads in the fabric.

25 In the drawings I have illustrated one of the many kinds of cloth which are adapted to have my invention applied thereto.

$a a$ represent warp-threads of the cloth to 30 which my invention is applied, these threads being arranged in pairs.

$b b$ are also warp-threads, arranged between each pair of warp-threads $a a$.

$c c$ represent the upper woof-threads of the 35 fabric, and which may be made of silver, gold, or other metal, or of any fibrous material.

$d d$ are the lower woof-threads, which may also be made of any usual or preferred material.

By an examination of the drawings it will be seen that in weaving this cloth the warp-threads 40 $b b$ are interwoven and looped around the upper and lower woof, and also pass through between the alternate pairs of warp-threads $a a$, which latter occupy a common plane intermediate between the woof-threads $c d$. Thus a cloth is 45 produced in which the upper woof-threads, $c c$, are substantially uniformly spaced, the distance between them being practically determined by the number and size of the lower woof-threads, $d d$, which are inclosed between each loop of 50 the warp-thread b .

In view of the fact that the warp-threads b

are not only looped around upper woof-threads, but also pass down between part of the warp-threads and serve to secure woof-threads to other threads of the fabric, I designate such 55 threads $b b$ as "woof and warp tying" warp-threads, and designate the threads a "intermediate" warp-threads.

$e e$ are the embroidery-threads, which are supplied to the fabric by the use of a needle as 60 follows: I pass the needle and thread up through the fabric from the under side at such point as may be desirable to commence embroidering the pattern. I then insert the needle under the warp and woof tying warp-thread b which 65 passes over the adjacent upper woof-thread, c , at that point which is nearest to the place at which the embroidery-thread has been passed up through the cloth, and under the next succeeding loop of the warp and woof tying warp- 70 thread which passes over the same woof-thread, c , and the succeeding like loops, drawing the embroidery-thread underneath each of these loops to such distance as is desirable in working the pattern. 75

Under some circumstances I lay the embroidery-threads upon the upper woof-threads, and sometimes I lay them between the woof-threads and in close contact with the warp-threads a . For instance, if I wish to produce the lightest 80 shade possible with a given color of embroidery-thread I lay it upon the woof-threads, whereas if I wish to produce a darker shade with the same color of embroidery-thread I lay it between adjacent woof-threads, both positions of the embroidery-thread relative to the other threads of the fabric being illustrated in the drawings. Thus the embroidery-thread may be laid in a plane throughout its entire length, its upper surface being unbroken and 85 uncovered, except by the warp and woof tying warp-threads b , and as these threads are usually in fabrics of this character very small their presence above the embroidery-thread is scarcely noticeable, and when the embroidery-thread is placed between the woof-threads the entire surface of the figure presents a very 90 smooth and finished appearance. In fact, the work can be made much smoother with the embroidery-thread laid upon the woof-threads 95 than can be done by the ordinary methods of embroidery.

While in practice I prefer to pass the embroidery under all of the adjacent loops of the warp and woof tying warp-thread *b*, yet I do not wish to be limited to so doing, because by 5 passing it under even the alternate loops I can produce a figure having an even and smoothly finished surface. In fact, with some cloth woven in substantially the manner to which I have referred it might be found desirable to pass 10 the embroidery-thread under only the alternate loops in order to avoid covering too much of its surface by these loops.

It will of course be understood that I do not wish to be limited to the use of any particular 15 materials in working my invention, nor to the use of cloth of the precise character referred to, because my invention may be applied to other cloths which are woven in such manner that I can introduce an embroidery-thread 20 upon the upper surface of the woof-threads and underneath warp-threads which pass over and loop around said woof-threads, and pass between intermediate warp-threads, underneath which latter it would be impracticable 25 to introduce the embroidery-thread.

I am aware of English Patent No. 2,825 of 1872, and hence do not claim anything therein shown; but the fabric shown and described in 30 said English patent which approaches most closely to my invention differs essentially there from.

In my invention the embroidery-thread is held in place by a warp-thread which is looped over an adjacent woof-thread and passes down

between and below the intermediate warp- 35 threads, whereas in the English patent the chenille which is understood to correspond to my embroidery-thread is held in place by a warp-thread, which is looped under an adjacent woof-thread, and does not pass down between and 40 below the intermediate warp-threads.

What I claim is—

1. The herein-described improvement in the art of embroidery, the same consisting in inserting threads in contact with upper woof- 45 threads and under the warp and woof tying warp-threads, substantially as set forth.

2. As a new article of manufacture, a woven fabric having warp and woof tying warp- 50 threads, other intermediate warp-threads, upper woof-threads, and embroidery-threads held in place by warp-threads which are looped over the embroidery-thread and pass down between and below warp-threads, substantially as set forth.

3. In embroidery, an embroidery-thread arranged in contact with a woof-thread, and also with the upper surface of warp-threads, and secured thereto by warp-threads which encircle the upper portions of both the embroidery- 60 thread and the woof-thread to which it is applied, substantially as set forth.

In testimony whereof I affix my signature in presence of two witnesses.

KATE L. TARBOX.
